Primary Examiner — Philip S Hyder*Assistant Examiner* — Keith Frank*(74) Attorney, Agent, or Firm* — Don V. Kelly; Evans & Dixon, L.L.C.(57) **CLAIM**

The ornamental design for a plastic carry out food container, as shown and described.

DESCRIPTION

FIG. 1 is a front perspective view of a plastic carry out food container showing the new design;

FIG. 2 is an exploded front perspective view thereof with the lid detached from the base for clarity of illustration;

FIG. 3 is a front elevation view thereof with the base having the lid secured thereon;

FIG. 4 is a right side elevation view thereof with the base having the lid secured thereon;

FIG. 5 is top plan view thereof with the base having the lid secured thereon;

FIG. 6 is a bottom plan view thereof with the base having the lid secured thereon; and,

FIG. 7 is a perspective plan view at the bottom thereof with the base having the lid secured thereon.
